UNITED STATES PATENT OFFICE.

WADE JOHNSON, OF SPENCER, OHIO.

ANIMAL-RESTRAINER.

1,163,090.

Specification of Letters Patent.

Patented Dec. 7, 1915.

Application filed May 15, 1915. Serial No. 28,408.

To all whom it may concern:

Be it known that I, WADE JOHNSON, a citizen of the United States, residing at Spencer, in the county of Medina and State 5 of Ohio, have invented certain new and useful Improvements in Animal-Restrainers, of which the following is a specification, reference being had to the accompanying drawings.

10 My present invention relates to new and useful improvements in animal restrainers and has particular reference to those of the type worn by cows.

The principal object of the invention is 15 to provide a restrainer which may be readily applied to a cow's neck and provided with spiking or jabbing prongs which are positioned on each side of the cow's shoulder and are adapted to jab or prick the same, in 20 case she swings her head in an endeavor to reach her udder.

A more specific object of the invention is 25 to provide a restrainer of the character specified which includes a yoke which may be applied to the cow's neck and a plurality of spiking prongs which are carried by the yoke and are adjustably secured thereto so that they may be properly positioned on different cows.

30 The above, and other incidental objects of a similar nature, which will be hereinafter more specifically treated are accomplished by such means as are illustrated in the accompanying drawings, described in the following specification, and then more particularly pointed out in the claims which are appended hereto and form part of this application.

With reference to the drawings, wherein 40 there has been illustrated the preferred embodiment of this invention, as it is reduced to practice, and throughout the several views of which similar reference numerals designate corresponding parts, Figure 1 is a side elevation showing the device applied to a cow; Fig. 2 is an enlarged side elevation of the restrainer; and Fig. 3 is a top plan view.

As best disclosed as an operative entirety in Fig. 1 of the accompanying drawings, the 45 restrainer includes a pair of yokes 10 and 11, a pair of connecting plates 12 and 13, by means of which the yokes are connected to each other, and a plurality of spiking prongs 14 which are connected to the rearwardly disposed yoke 10 and are adapted to

5 operate in a manner to be hereinafter described.

The connecting bars are similar in construction and each includes, as best shown in detail in Fig. 2 a substantially rectangular body portion 15, and a transverse head plate 16, from the terminals of which extend the right angularly directed parallel ears 17. The head plates of the connecting bars are secured by bolts, rivets or equivalent fastening devices, as indicated at 18 to the rearwardly disposed yoke 10 and to the side portions or arms thereof, as in Fig. 2. The forward ends of the connecting bars of the body portions are pivotally connected as by bolts or similar devices 19 to the arm portions of the forward yoke 11. Each yoke member is accompanied by a buckle and billet, as indicated at 20 and 21, so that the yokes may be secured upon the cow's neck. 75

The upper and lower faces of the upper and lower ears respectively of each head plate are provided with ratchet teeth 22. The inner ends of the prongs 14 are provided with integral disks 23 which are also 80 provided on one face with ratchet teeth 24. The disks of the prongs are mounted upon the ears of the connecting bar head plates and are disposed with their ratchet teeth in engagement with the ratchet teeth 22. Bolts 85 indicated at 25 are passed through each disk and its associated ear for holding the two members in engagement with each other.

From the foregoing description, it will be 90 readily apparent that the prongs may be adjusted to space their pointed terminals different distances, whereby the device may be accommodated to cows of different sizes. The prongs are preferably given a slight longitudinal curvature. 95

Reference is now had particularly to Fig. 1, in which the device is illustrated in use. In this figure it will be seen that a pair of prongs is disposed on each side of the cow's head so that in case the cow endeavors to 100 suck her own udder, she will be restrained from so doing by the prongs which will pierce or stick the tender portions of her shoulders.

While it is preferable that the yoke 11 be 105 free for pivotal movement relative to the members 15, it is of course possible, when conditions make it advisable, to secure the member 11 against movement with respect to the members 15 by tightening the nuts 110

upon the bolts 19. A further feature to be noted is that the prongs 14 may be adjusted to allow the cow to move her head the requisite distance for feeding. By making 5 the straps 21 relatively long, the yokes 10 and 11 may be employed in connection with cows of different sizes.

In reduction to practice, it has been found that the form of this invention illustrated in 10 the drawings, and referred to in the above description as the preferred embodiment, is the most efficient and practical; yet realizing that the conditions concurrent with the adoption of this device will necessarily vary, 15 it is desirable to emphasize the fact that various minor changes in the details of construction, proportion and arrangement of parts may be resorted to, when required, without sacrificing any of the advantages 20 of this invention, as defined by the appended claims.

What is claimed is:—

1. An animal restrainer including a pair 25 of neck yokes adapted to embrace the animal's neck, a pair of plates connecting the yokes, the plates being rigidly secured to one yoke and being pivotally attached to the other yoke, and a plurality of spiking prongs carried by one of the yokes.
2. An animal restrainer including a pair 30 of yoke members, connecting plates extending between the yoke members, one of said yokes being fixed to the terminals of the connecting plates, the other of said yokes being 35 pivotally supported between the other terminals of the plates, and a plurality of spiking prongs attached to the first mentioned yoke and mounted for adjustment whereby the terminals of the prongs on opposite sides 40 of the yoke may be spaced different distances from each other.
3. An animal restrainer including a pair 45 of yokes, plates connecting the arms of the yokes, and a plurality of spiking prongs attached to the rear terminal of each plate,

said prongs being mounted for angular adjustment in a horizontal plane.

4. An animal restrainer including a pair of yokes, plates connected in the arms of the yokes, one of said yokes being relatively 50 fixed to the rear terminals of the arms, the other of said yokes being pivotally supported between the forward terminals of said plates, lateral ears extending from the rear terminals of each plate, and a plurality of 55 piercing prongs having their terminals rotatably mounted upon the said ears, whereby the free ends of the prongs may be adjusted to different angular positions to accommodate the restrainer to animals having 60 shoulders of different widths.

5. An animal restrainer including a yoke adapted to be disposed upon the forward portion of the animal's neck, a yoke adapted to be disposed at the base of the animal's 65 neck, a pair of connecting plates, the second mentioned yoke being relatively fixed between the rear terminals of the plates, the first mentioned yoke being pivotally supported between the forward terminals of 70 the plates, said plates being provided at their rear terminals with horizontally extending apertured ears, each of said ears being provided on one face with ratchet teeth, a plurality of spiking prongs, each of 75 said prongs being provided with a disk at one terminal, said disk being provided with ratchet teeth, the disks of the prongs being adapted to seat upon the ears with the teeth of the 80 disk engaging with the teeth of the ears, and clamping bolts passing through each ear and its associated disk for securing the prongs in adjusted position.

In testimony whereof I hereunto affix my signature in the presence of two witnesses. 85

WADE JOHNSON.
